MULTIPLE COIN-OPERATED PHONOGRAPH CONTROLS

Frank Sager, Ahmeek, Mich.

Application September 8, 1948, Serial No. 48,237

1 Claim. (Cl. 179—6.3)

1

The present invention relates to the general class of sound recording and reproducing appliances, or mechanical phonographs of the flat multi-record type, and more specifically to multiple coin operated phonograph controls which while adapted for various purposes and uses, are designed as portable units, one of which is operatively installed within each of two or more phonograph structures, and connected with the operating circuits of the system of phonographs. The primary purpose of the invention is to control the operation of one of two, or more, phonographs in an electrically connected system, and to prevent the mechanical or automatic operation of other phonographs in the system simultaneously with a selected phonograph. Means are also provided, however, for allowing another customer or customers, to select a desired number or numbers for one or more of the other phonographs in the system after depositing a coin in the phonograph, and these selected numbers will be played only after the first operating machine has ceased to play its number.

Another object of the invention is to provide an electrical control unit for a pair of coin-controlled electrically-operated phonographs which will permit only one of the phonographs to operate at a time in the event that a plurality of coins are inserted in the phonograph.

For convenience in illustrating and describing my invention only two phonographs or machines of the coin operated type are herein employed in which the control units are readily adapted to, and they may with facility be installed within the phonographs of a system, and these control units successfully perform their functions in the operating circuits in standard types of coin operated phonographs having record changing mechanisms.

The invention consists in certain novel combinations and arrangements of the electrical wiring and electrical appliances in the control units and the operating circuits as will hereinafter be described and more particularly set forth in the appended claim.

In the accompanying drawings I have illustrated a complete example of a physical embodiment of the invention in which the parts are combined and arranged in accord with one mode I have devised for the practical application of the principles of my invention. It will, however, be understood that changes and alterations are contemplated and may be made in these exemplifying drawings and electrical arrangements, within the scope of my claim, without departing from the principles of the invention.

2

Figure 1 is a diagrammatic view in section showing two coin operated phonographs representing a controlled system, each of which is equipped with the electric control of my invention.

Figure 2 is an electrical diagram of the wiring and electrical appliances of one of the portable control units.

Figures 3 and 4 are respectively end and side views in elevation of the electrical control unit; and

Figure 5 is an electrical diagram of the wiring and appliances of the two electrically connected phonographs in a system.

For a clear understanding of my invention I have shown in Fig. 1 two typical coin-operated automatic phonographs A and B which may be spaced apart and located at desirable points in places of amusement and entertainment, or in other public places for the convenience of customers or patrons. Each of the phonographs is equipped with a control panel J, speakers D, a turn-table or record carrier E with its tone arm G, a stack of records or disk tablets R and the changing mechanism, and other necessary equipment as amplifiers H, motors, cabinet lights etc.

In carrying out my invention each of the phonographs A and B has installed therein a portable control unit shown diagrammatically in Fig. 2 which includes a control panel that has a plurality of female jacks P mounted on a frame plate F that is installed within the cabinet of the respective phonographs, the control panel constituting a junction box. The wiring includes input wires 1 and 2 that are connected with a step down transformer T, of the iron core type, and mounted on the frame plate F. By means of output wires 7 and 8 from the transformer to a relay or solenoid S, electrical energy is supplied for the switch circuits 3 and 4 and 5 and 6, for operating control switches 34 and 36 under control of the solenoid; and a fuse 9 is interposed in the output wire 8 for emergency purposes in the portable control unit.

45 The transfer T has the same input voltage requirement as that employed in its equipped phonograph, and the output of the transformer is of ample capacity to hold the armature of the solenoid S and open the respective control switches 34 and 36 of the speakers D, D; and the fuse 9 operates to protect the solenoid.

For installing the respective control units in the phonographs A and B, some of the wires of each of the control units, as well as the electrical equipment of the phonographs, are provided with attachable electrical connectors, or termi-

nals of the plug and socket type and provision is made on the control panels J, J, for these connections. In Fig. 1, where the portable units are installed in the respective coin phonographs A and B; and in the diagram of electrical wiring in Fig. 5; in order to supply ample voltage to the transformers T, T, two wires 10 and 11 from junction box J of the phonograph A are plugged into the jack P of the control unit of machine or phonograph A, and two wires 12 and 13 from panel J of the phonograph B are plugged into the jack P of the unit of phonograph B.

Current for the switch circuit 3-4 of phonograph B is supplied through wires 14 and 15 that extend from junction box J of machine A and are plugged into the jack P of phonograph B; and wires 16, 17 from panel J of phonograph B are plugged into the jack P of machine A for supplying current to the switch circuit 3-4 of phonograph A.

Electrical energy for the switch circuit 5-6 of phonograph A is supplied from the amplifier H of phonograph B by wire 18 plugged into the jack P of phonograph A, and a wire 19 which also is plugged into this jack connects to the speaker D of the phonograph B.

In the same manner wires 20 and 21 which supply current for the circuit 5-6 of phonograph B connect the amplifier H of phonograph A in series with the speaker D of the phonograph A; and the field coil-wires 19 and 21 are tapped and connection is made between the two speakers by wire 22.

The two speakers are also connected by three wires 23, 24, and 25, that are tapped by wires 26, 27, and 28 and connected to the amplifier of phonograph A; and also tapped by wires 29, 30, 31 which connect them with the amplifier of phonograph B.

When a coin is inserted in the phonograph A, for instance, power is supplied to its motor and to its amplifier H, and the phonograph proceeds through its regular cycle of operation. At the same time, power is also supplied to the transformer T of the multi-coin-operated control unit in phonograph A and the output of this transformer energizes the solenoid S in the same unit of the A phonograph. Energy from the transformer pulls down the apron or armature of the solenoid thus breaking the initially closed contact points of switches 34 and 36 of the control unit in phonograph A. The breaking of one set of these points in machine or phonograph A prevents the mechanical operation of phonograph B because this breaks an electrical circuit to the junction box J of machine B; and thus the breaking of the second set of points prevents a possible back-up of electrical energy or power

into the amplifier H of the inoperative phonograph B.

When a coin is deposited in phonograph B, the initially closed switches 34 and 36 are opened in this phonograph, and circuit wires 10 and 11 are interrupted in the box J of phonograph A to render inoperative this phonograph.

The two speakers D, D, are electrically connected and constantly operative, and the operator, by depositing a coin in phonograph A may thus play his selected record, which is reproduced through both speakers; and, of course the same procedure may be followed by an operator depositing his coin in the phonograph B for a re-production through the B and the A speakers D.

Selections may be made on the B phonograph by depositing a coin while the A phonograph is playing, but the mechanical operation of the B phonograph will not start until such time as all the selections on phonograph A have been played. At such time when phonograph A is at rest and idle, phonograph B immediately starts its operation and plays its selection that had been previously selected.

Having thus fully described my invention, what I claim as new and desire to secure by Letters Patent is:

In combination, a pair of coin controlled phonographs, means electrically connecting said phonographs together, each of said phonographs including a motor and an amplifier, an electrical control unit and circuit for each of said phonographs including electrical input wires, a step down transformer connected in the circuit to said input wires, output wires from said transformer, a relay connected to said output wires, control switches under control of said solenoid, a fuse interpolated in one of the output wires from the transformer for protecting said solenoid, and said control switches serving to de-energize the motor of one of said phonographs when the motor of the other phonograph is energized while the speakers of the phonographs remain electrically connected together.

FRANK SAGER.
